UNITED STATES PATENT OFFICE.

GUIDO ALFONS HEDBERG, OF ALINGSÅS, SWEDEN.

MANUFACTURE OF EXPLOSIVES.

1,335,785.

Specification of Letters Patent.

Patented Apr. 6, 1920.

No Drawing.

Application filed September 9, 1919. Serial No. 322,715.

To all whom it may concern:

Be it known that I, GUIDO ALFONS HEDBERG, a subject of the King of Sweden, residing at Alingsås, in the county of Alfsborg and Kingdom of Sweden, have invented new and useful Improvements in the Manufacture of Explosives, of which the following is a specification.

This invention refers to an improvement 10 in the manufacture of explosives.

In the manufacture of gelatinized explosives it is known to mix in cork-powder or similar substances so that the air contained in the cells of the said aggregates may increase 15 the detonating effect of the explosive. Said substances however are difficult to procure particularly in places, where they are not to be found as natural products. It has also appeared that the said aggregates 20 are not adapted to powder shaped explosives now more and more usual, such as nitrate of ammonia or similar, where it is proved fit to bed intimately the explosive proper into a protecting covering.

This invention is a result of experiments 25 to find some aggregates more suitable than those hitherto known. It has namely appeared, that fine-ground meal of pine-bark as an aggregate, especially in powder shaped 30 or granular explosives, gives the same a particularly increased effect as also a greater ability to endure storing without losing in explosive effect by taking up moisture. This good effect of the meal of pine-bark 35 appears still more evident, if to the meal of the pine-bark is added some per cent. meal

of pine-cones, which per cent. however may vary within rather extensive limits, viz., between 0.5% and 20%.

The good effect of the meal of pine-bark 40 and the meal of pine-cones on the explosives may be ascribed to their percentage of resin or incrusted substances.

When manufacturing an explosive in accordance with this invention the explosive 45 material is thoroughly mixed with the meal of the pine-bark, intermingled with meal of cones, so that the grains of the granular explosives are caused to be intimately embedded within the bark- and cone-meal. 50

Having thus particularly described and ascertained the nature of my said invention and how the same is to be performed I declare, that what I claim is:

1. In explosives, in combination with the 55 explosive materials proper, meal of pine-bark and meal of pine-cones as an intimate mixture.

2. Explosives as claimed in claim 1 the 60 quantity of cone-meal representing 0.5 up to 20 per cent. of the meal of pine-bark.

3. An improved method of manufacture 65 of explosives, characterized therein, that granular explosives are thoroughly mixed with aggregates of meal of pine-bark and meal of pine-cones, so that the explosive grains are caused to be intimately embedded in the bark-meal and cone-meal.

In testimony whereof I have affixed my signature.

GUIDO ALFONS HEDBERG
